GARMENT HANGER

Carl S. Bjorklund, Edgar C. Bjorklund, and Edsel T. Bjorklund, Milwaukee, Wis.

Application October 1, 1945, Serial No. 619,482

1 Claim. (Cl. 223—91)

1

Our invention refers to garment hangers and it has for its primary object to provide a combination hanger wherein, for example, coats, trousers and skirts may be conveniently suspended therefrom. Thus the garments, being suspended from a single unit, will materially economize in closet space, bearing in mind that under usual conditions a coat and vest require a hanger and the trousers require a second hanger. Furthermore, a single unit is particularly useful for cleaners or tailors in delivering garment articles.

The specific object of our invention is to provide a garment hanger comprising essentially a yoke having a backing piece extending thereacross with a pair of spring clips attached to the backing piece, whereby the legs of trousers may be quickly slipped into the clips for suspending the same under the coat in a compact unit.

With the above and other objects in view, which will appear as the description proceeds, the invention resides in the novel construction, combination and arrangement of parts, substantially as hereinafter described, and more particularly defined by the appended claim, it being understood that such changes in the precise embodiment of the herein disclosed invention may be made as come within the scope of the claim.

In the accompanying drawing is illustrated one complete example of the physical embodiment of the present invention constructed according to the best mode so far devised for the practical application of the principles thereof.

In the drawing:

Figure 1 represents a perspective view of a garment hanger embodying the features of our invention.

Figure 2 is a plan sectional view of the same, the section being indicated by line 2—2 of Figure 1.

Figure 3 is a similar sectional view showing the legs of trousers gripped therein, and

Figure 4 is a fragmentary cross section of the hanger, the section being indicated by line 4—4 of Figure 1, the same being illustrated as having trousers legs gripped therein.

Referring by characters to the drawing, 1 indicates a yoke formed from a single piece of wire having a bottom connecting strip 2 and a suspension hook 3, all of the same being standard and form no part of the invention.

The downwardly inclined yoke wires 1—1 are provided with vertically positioned offsets 1' for the reception of a double wire backing piece 4, which backing piece is looped about the yoke offsets 1' to effect a joint. From this joint the

5 double spring wires are folded against the backing strip to form spring clamps 5—5. The clamps terminate at their ends with gripping loops 6—6, which gripping loops are spaced apart to form a throat for the reception of a garment such as trouser legs, or the like.

The backing piece 4 and spring clamps 5 may be secured together by solder or welding patches 4'—4'', the latter serving to secure the ends of

10 the loops 6.

As best indicated in Figures 3 and 4 of the drawing, when it is desired to insert the legs of a pair of trousers into the hanger, one of the spring clips is pulled outwardly to form a throat, 15 whereby one edge of the trouser legs is inserted between the clamp and backing piece 4. The opposite gripping clamp is then pulled out, under spring tension, whereby the other creased edge of the trouser legs, as indicated at A, is inserted 20 into the throat. Thus said trousers are firmly held in position, as indicated in Figures 3 and 4, it being understood that due to the spring clamps, the trousers are securely held in suspension irrespective of the fact that they may or may not 25 have cuffs at their bottom edges.

Under usual conditions the coat or coat and vest are then inserted over the yoke and, should it be desired, another garment may be hung over the strip 2.

30 Obviously, in some instances, we may dispense with the connecting strip 2, and while we have shown the yoke and backing piece 5 fabricated from wire, these parts may be formed from a single flat backing of wood, paper fiber, or other material, in which instance the spring clamps 35 would be secured thereto.

It is also within the scope of our invention, in some instances, to provide a long single spring clamp as a substitute for the two clamps shown 40 in this exemplification of our invention.

We claim:

45 In a garment hanger provided with downwardly inclined wires, connected by a cross strip, the inclined wires being offset above the cross strip to form vertically disposed seats, a trouser support for the hanger comprising a double wired backing piece looped about the yoke offsets and folded upon itself to form spring clamps associated with a back, the clamp ends terminating 50 with gripper loops spaced apart to form a garment receiving mouth.
